ABSTRACT

Described are techniques for stabilizing, restoring the ground-cover in Arctic (or like, frozen) environments including, in specific embodiments, techniques for: restoring and revegetating a spoil pond for spent drilling mud; refreezing and insulating of "pond crossings"; restoring "winter roads" and like tundra scars; leveling "arctic roads" and constructing ice foundations for arctic pads.

14 Claims, No Drawings

STABILIZING ARCTIC GROUND COVER

BACKGROUND OF THE INVENTION

More and more, man's activities in the Arctic threaten to disturb the tundra ground cover there. For instance, in exploring Arctic regions for mineral deposits, some workers have constructed what are known as "winter roads", or piled-up frozen tundra. In the exploration and development of petroleum deposits, roads are increasingly needed across "ponded areas"; other roads present the problem of stabilizing rain-ditches; also mud sump-spoil ponds are built which, when they are no longer used, should be restored to harmonize with the ambient ecology.

Some arctic roads comprise simply a layer of gravel spread upon the Arctic plain, over the tundra and underlying permafrost, with the result that, over a period of time, the roadsides, and any ditches that may have developed there, fill with water presenting an obvious hazard, both to the integrity of the road and to the stability of the adjacent Arctic groundcover.

A related problem exists where "winter roads" are constructed; these comprising simply a piling-up of frozen ground cover during winter (e.g., by bulldozers simply blading-up tundra on one or both sides of the right of way) to present a raised earthen-tundra "berm" above the surrounding ice and snow, typically a few feet high and a few feet wide. Such "winter roads" are being discouraged at present, with the existing "berms" being destined for leveling and later restoration of the native vegetation, etc. However, when the tundra back-fill is distributed back over the marginal ditches (now typically eroded or subsided), a gully often remains — which, if not treated, will leave a gash externally scarring the natural topography of the arctic plain. It is well-known that such scars are often self-perpetuating and self-eroding in time and, thus, must be prevented or corrected wherever possible. Contemporary restoration methods involve filling the marginal ditches with gravel or arctic dune sand to bring the eroded section up to tundra grade, thereafter distributing the tundra material on this and reseeding. Unfortunately, this technique is not only expensive but, due to the poor insulation such materials provide typically fails to prevent melting of the subjacent permafrost and eventual erosion or subsidence. Similar problems result from vehicular tracks left in the soft summer tundra and from thin-layer gravel roads.

A related problem exists with mud sums or other spoil ponds, such as are found adjacent to oil field drilling pads on the Alaskan North Slope. Mud Sumps or many types may be found in the Alaskan and Canadian Arctic as a result of past drilling operations, many being abandoned in various stages of disrepair. These sums are typically built simply by the excavation of a cavity in the tundra and the piling up of excavated soil and vegetation to form a "berm" perimeter around the cavity, thereby defining a sump pond in which drilling "mud" is to be kept. Spent drilling mud is at times left in such a pond without any further disposal efforts. However, it is presently advisable to remove the mud and dispose of it in a less offensive manner and fill the cavity with earth material. Typically, a sump base-level is close to "tundra grade" with its perimeter "berm" about 5 feet above grade. It is obviously important to restore this berm material back over the tundra surface

(e.g., to cover the sump pit) as well as to remove the excess spent mud and dispose of it in a practical, economical and ecologically-satisfactory fashion. The temptation is to scatter the mud about, e.g., over the adjacent tundra or along nearby gravel roads to the involved drilling site. However, certain muds (in excess) may have a toxic effect on tundra vegetation and/or present a "dust problem" since it comprises a fine aqueous suspension readily drying to a light, fine dust. 10 Similarly, it is very unsatisfactory, if not hazardous, as a roadway coating. Also, it is rather expensive to dispose of mud in such a manner. Moreover, the presence of such spoil ponds atop a permafrost formation, increasing its susceptibility to melting, obviously presents 15 the hazard of melt-subsidence and serious erosion.

As an answer to the foregoing and related problems, we have developed techniques according to various features of the present invention that involve such expedients as freezing the liquid formation (in such a rain-ditch or spoil-pond area); and then restoring these areas to become an integral part of the subjacent permafrost by covering them with sufficient insulation to keep them frozen, laying on earth-fill over the insulation (e.g., with berm material) to restore the area to 20 tundra grade, and then a special reseeding treatment for restoration of tundra vegetation. According to some more particular features, a very simple, inexpensive foam insulation may be used, together with certain optimal techniques of seed selection, fertilization and application.

ARCTIC GROUND COVER

Land masses above the Arctic Circle typically exhibit a "tundra" ground cover made up of a biological insulating mat, 2 to four inches thick and comprises of various sedges, grasses, miniature shrubs, etc. Beneath this mat is an "active layer" of top-soil 6 to 18 inches thick, ordinarily made up of slit, sand and organic matter (this supporting the tundra vegetation). Below the "active layer" one typically finds a "permafront" stratum; i.e., an aqueous mixture of earth (rock, soil) material in various proportions (and sometimes comprising pure ice) and extending as far down as 1,000 feet or more. The active layer of the tundra will thaw each summer, with the insulative properties of the tundra and the degree days of summer thaw controlling the depth of thaw in the active layer. In the winter, air temperatures can dip below -60°F., with wind velocities up to and even exceeding 50 m.p.h. Because this climate is so frigid and the arctic summer so brief (typically a few weeks) and because the average temperature of the ground-surface is so low, the vegetative growth each year is typically minuscule. Moreover, many tundra soils are nearly sterile with extreme deficiencies in more than one of the primary nutrients (nitrogen, phosphate and potash). The typical grass and brush vegetation is thus quite sparse, dwarfed and starved; moreover, organic decay and bacterial action are extremely slow and seed yields are often low. Thus, understandably, natural re-vegetation of tundra is a very slow, tedious affair, and all too unpredictable.

After some study and evaluation of typical tundra vegetation systems, a reseeding program was proposed with the following objectives:

TABLE I — RESEEDING OBJECTIVES

1. Establishment of grasses in damaged areas by in-

roduction of specially-selected, seeds which germinate rapidly and grow vigorously in the limited Arctic growing season;

2. Propagation and proliferation of native grasses in restored areas by stimulation, peripheral vegetation to enhance reinvasion and restore natural vegetative insulation over permafrost formations; and

3. Stimulation of native seed production on peripheral undisturbed areas by use of selected, specially formulated fertilizers and supplements to promote this reinvasion of prior restored areas and gradual return to the natural state.

In support of this program, an investigation was undertaken of typical soil nutrients with a view towards formulating adequate fertilizers for the foregoing objectives. Soil samples were taken from the plant-supporting active soil layer in the Prudhoe Bay and Sagwon areas of the Alaskan North Slope. The results are shown in Table II below.

TABLE II — TUNDRA SOIL ANALYSIS

	Prudhoe	Sagwon	Desired(a)
pH	8.1	8.0	6-7
P ₁ (as P ₂ O ₅) (available pound/acre)	15	15	60-80
P ₂ (as P ₂ O ₅) (non-available pound/acre)	15	15	0
K ₂ O (pound/acre)	75	220	360—
Ca (pound/acre)	13,200	14,400	6000-8000
Mg (pound/acre)	224	368	150-900
Zn (pound/acre)	1.6	1.4	8-12
Cu (pound/acre)	0.6	0.6	6-10
Fe (pound/acre)	1.2	1.6	45
Mn (pound/acre)	22	18	20-30
B (pound/acre)	2.6	5.6	1-3
S (pound/acre)	33	36	40-50
Na (pound/acre)	237	166	40
Organic Matter (Wt. %)	60.6	55.5	5-10

(a) Amounts based on agricultural crop production in the Continental U.S.

Both samples evidence an excess of calcium and sodium. Boron, sulfur and manganese appear sufficient to support plant growth; however, deficiencies were found in available phosphorus, potassium, nitrogen, zinc and copper and iron; while pH was somewhat too alkaline. A similar soil sample taken at the Prudhoe Bay location, adding subsurface samples and giving the results indicated in Table III below.

TABLE III — TUNDRA SOIL SURFACE AND PERMAFROST ANALYSIS (PRUDHOE BAY)

DEPTH (ft.)	0	10	12	13	15	17	18
Water (Wt. %)	23.8	62.4	80.4	34.5	17.5	13.7	8.0
pH	7.8	7.4	7.3	7.9	8.3	8.4	8.5
P ₁ (lb./acre)	13	9	5	8	10	9	
P ₂ (lb./acre)	20	23	43	72	88	69	
K ₂ O (lb./acre)	70	20	115	125	250	290	105
Ca (lb./acre)	9800	18,000	14,000	7800	8200	8000	3400
Mg (lb./acre)	400	400	760	200	280	280	280
Mn (lb./acre)	46	28	29	47	43	40	57
Zn (lb./acre)	1	2	6	1	1	3	2
Fe (lb./acre)	104	256	262	61	104	122	122
Cu (lb./acre)	5	7	6	5	4	7	6
B (lb./acre)	1.3	1.1	2.2	4.8	1.2	0.6	2.0

These results agreed, generally, with those in Table II except for the higher iron content. By taking samples during drilling operations, the soil specimens at the indicated sub-surface depths were obtained. Variance from the other samplings would be typical of tundra composition difference over short sampling distances.

In accordance with a feature of the instant novel tundra restoration system, a special tundra fertilizer, 10 "Tundra Special-70", was developed to increase soil fertility, being formulated especially for a Prudhoe Bay locale. This was to be applied at approximately 600 pounds/acre concentration, being formulated to add P₂O₅, K₂O and N plus trace minerals as indicated in Table IV below.

TABLE IV — "TUNDRA SPECIAL-70" FERTILIZER

20	Component	Percent by Weight
N (Nitrogen)		11.52
P ₂ O ₅ (Phosphate)		34.56
K ₂ O (Potash)		8.64
Ca (Calcium)		.03
Mg (Magnesium)		.21
SO ₄ (Sulfate Sulfur)		4.57
Al (Aluminum)		—
B (Boron)		0.0392
Cu (Copper)		0.1344
Fe (Iron)		0.676
Mn (Manganese)		1.0768
Zn (Zinc)		1.01
Mo (Molybdenum)		0.00098
Inert Filler		Balance

Very little nitrogen release from the existing organic matter may be expected in such locales and is believed to be a temperature-dependent, bacteriological function. It is known that the nitrogen-converting bacteria (nitrosomonas and nitrosococci) are less active at 50° F., and become virtually ineffective at lower soil temperatures. At Prudhoe Bay the mean annual soil surface temperature is typically about 12° F.; whereas a typical value for mean soil surface temperature in an 800 degree day summer will be 40° F.

It is estimated that the top 2 inches of soil in each acre of this locale comprises approximately 666,000 lbs. of soil containing approximately 40,000 lbs. of nitrogen. It is estimated that the nitrogen release is not more than about .025 to 1.0 percent annually, or not more than 10 to 40 pounds of nitrogen released per acre per year. By comparison, the nitrogen release in typical organic soils in the "lower 48" ranges from 1 to 5 percent annually, or 20 to 120 pounds per acre per year. Accordingly, this special fertilizer was especially fortified with nitrogen. In certain other locales, ammonium nitrate is added as a supplemental nitrogen source.

SEED SELECTION

The preferred approach for revegetating disturbed tundra areas is to reintroduce native biological species. As a matter of convenience, arctic grasses are preferred over other Arctic flora. Table V summarizes a survey of plant forms around the Naval Arctic Research Laboratory at Point Barrow, Alaska. It is representative of the Arctic flora (particularly grass species) found in much of the North Slope.

TABLE V — ARCTIC FLORA — BARROW,
ALASKA (BASED ON TAXONOMICAL STUDY BY
HULTEN)

Family	Generic Class	Variety	Common Name
Equisitaceae

Native seeds for revegetation were considered; however, seed production of Arctic tundra biospecies is not very predictable since their seed set appears significant only in those years having over about 800 degree days of thaw. Below this "thaw index," native seed production will be low; above it, a fair to good seed yield can be realized. Also, harvesting seeds from actual tundra flora would require running the associated equipment over the soft delicate tundra surface during summer — the time of maximum seed-set and of maximum thaw penetration. Such a harvest operation would, in itself, likely cause damage. On the other hand, cultivated production of such seeds at the commercial level will require years of development. Thus, for "instant introduction" of revegetation in disturbed tundra areas, using native seeds does not appear feasible at present.

Accordingly, commercially-available seeds whose generic characteristics bear a relationship to those of native species were screened. Well over a hundred grass

types were considered before 13 "winter-hardy" strains (from northern climates) were selected, these being listed in Table VI below.

TABLE VI — GENERIC RELATION OF
INTRODUCED VS NATIVE TUNDRA-TYPE
GRASSES

5	INTRODUCED GRASSES		NATIVE ARCTIC TYPE GRASSES		Longitude Found
	10	SCIENTIFIC NAME	15	SCIENTIFIC NAME

de-
scribed,

Investigations with various seeds and appropriate fertilization indicated that red top, creeping red fescue and brome did well when properly fertilized. Also, a cover crop of oats or barley appear to be quite beneficial for good seedling development. Moreover, fertilization tends to increase percent germination and promote good seedling development.

Seeds were also treated with gibberellic acid (GA), as a "growth hormone." Most seeds treated with G.A. and water will exhibit better overall germination, the concentration varying however; with seedling develop-

ment being usually observed on the order of 1 to 2 weeks ahead of that in untreated and fertilized plots (see Table VII).

TABLE VII — SAMPLING A: PHENOTYPE RATINGS OF GRASS TYPES IN GROWTH HORMONE TEST

SOURCE	G.A. CONCENTRATION			Water only
	25 ppm	50 ppm	100 ppm

Oats	V.G.	F.	F.	V.G.
Timothy	V.G.	V.G.	V.G.	V.G.
Meadow Fescue	V.G.	V.G.	V.G.	V.G.

Seedling development ratings: Very Good: V.G.; Good: G.; Fair: F.; Poor: P.; Very Poor: VP

Several grasses did not respond to differential growth hormone treatment. These are Brome, Olds Red Fescue, Meadow Foxtail, Boreal Red Fescue, Timothy, Elbin Rye, Israel Sweet Clover and Meadow Fescue. Conversely, some responded to high concentrations of GA (100 ppm), namely: Perennial Rye, Canada Blue, Stream Bank Wheat, Nugget Blue, Slender Wheat and Creeping Red Fescue.

Surprisingly, some species performed best with incipient water treatment alone, indicating that a 25 to 100 ppm concentration produced an inhibiting effect upon germination. These were: Arcta Red Fescue. Other grass species showed better response with 50 and 100 ppm; namely: Perennial Rye and Tickle Grass.

In summary, Red Top, Creeping Red Fescue, Brome and Canada Blue Grasses planted in the Prudhoe Bay area on disturbed tundra and gravel areas exhibited good winter survival and growth continuation — surprisingly so in view of past knowledge and experience! Also noteworthy were the advantages derived from growth hormone treatments; namely, enhancing initial germination and growth, as well as reducing residual seed germination (seed that did not germinate the 1st year) and winter kill. Hormone treatment however is a very selective thing, since some of the specimen grasses did as well with a simple water pre-soak as with a 25 ppm GA treatment (1 year's growth as the standard).

POND STABILIZATION EXAMPLE — GENERAL

Now, a specific example of using the tundra icing/restoration techniques according to the invention will be described in connection with rehabilitating a spoil pond (or sump) for drilling mud which was built on the tundra in the Alaskan Prudhoe Bay area. Such a sump is typically constructed by excavating a cavity of suitable size (here: 100 × 150 feet; 6 feet below tundra grade)

into the arctic plain, piling up "active layer" and "tundra" material to form a suitable perimeter barrier (or "berm") above grade (here, about 4 feet above grade; and about 10 feet wide). An underlying permafrost stratum will, as expected, be understood (here, beginning about 5 feet below grade, the excavation, thus cutting into the top foot of permafrost here). This sump, as is typical, will be understood as located adjacent a drilling pad and substantially filled with spent drilling mud. It is further understood that the warm mud and ambient heat will have caused a degree of meltsubsidence in the underlying permafrost, thus creating a waste liquid pool considerably deeper than originally constructed (note: this sump has lain abandoned for about a year with its liquid level equilibrating at about 6 feet below grade). During the "early spring," preferably at the beginning of April, this spoil pond is to be "iced-in" and insulated, and restored according to the invention. (Ice formations are at their coldest and at 20 their greatest depth at this time of year in this locale).

The general approach will be to apply a thin protective pre-coat (preferably using a crude-oil base) to the surface of the frozen mud. However, it is also preferred to first cut away the inner shoulder of the berm to form an inclined "inner shelf" about 1 to 2 feet wide (around the inside of the berm and extending outward from the edge of the frozen mud and downward at about 45° therebeyond). When insulation-coated, this "inner shelf" accommodates a downwardtilting "brim" extension of the liquid (insulation) cap, about 1 foot wide. A urethane foam insulation coating is then applied to a thickness of 1 to 2 inches. This is followed by a "barrier coating" (preferably, but not limited to, a mixture of polymers in a petroleum base) for a weather seal. Thereafter, the berm is pushed in over the coated insulation cap as "resealable fill," sufficient to restore the grade level. The top surface of this fill is then fertilized and planted in a prescribed specified manner (tailored to the vegetative needs of the subject locale).

The leveling fill, once covered with revegetation, will function, as thermal insulation over the underneath permafrost, as will the insulated pond-ice, acting to stabilize the site, restoring it to ecologically-compatible integrity with the native ground cover, with the permanently-frozen mud-ice being kept frozen to be integrated with the underlying permafrost (forming a "quasi-permafrost") and so providing a solid, stable footing for revegetation and for restoration and total integration with the surrounding native site.

POND-STABILIZATION: DETAILS

The foregoing restoration steps will now be described in more detail.

PHASE 1 — PRECOAT:

The (100 × 150 feet) frozen surface of the pond, together with the peripheral shoulder, are coated with a warm layer of "ARCOTE" or other suitable precoat to a depth of about 15 mils., this being applied generally as known in the art, using conventional manual hot-spray equipment, heated to about 75°F. (for typical April conditions in this locale) so as to help flow the precoat onto the substrate and get fast "set up." Although other equivalent materials will come to mind, this ARCOTE is the preferred "polymer-extended crude-cut," comprising an homogeneous mixture of "Prudhoe Bay residual crude" (from a diesel "top

cut"), extended (on the order of about 15 vol. percent) with polybutadiene as a polymeric extender, or with a like extender (e.g., polyethylene or polystyrene). Of course, any application method, temperature, etc. will serve that applies the material in a quick, even coating as understood by those skilled in the art. Other petroleum base pre-coat materials may be used such as residual fuels, or even certain resins; however, it will be appreciated that for the subject locale, the aforementioned Prudhoe residual cut is especially convenient, inexpensive and practical. The extender materials may comprise any compatible polymeric "checkers agents" which act to promote formation of a "skin" upon cooling.

PHASE 2 — FOAM INSULATION

Once the pre-coat has sufficiently "set-up" so as it be relatively firm (skin formed), a layer of polyurethane foam about 1.3 to 1.5 inches thick is applied thereover and allowed to cure, at least until it is set up. A different pre-coat may be called for with various differing ambient (thermal, soil, moisture, etc.) factors and/or different purposes (see also copending, commonly-assigned U.S. Application Ser. No. 205,381 entitled Structure for Protecting and Insulating Frozen Substrates and Method for Producing Such Structures by A. C. Condo, G. R. Knight, G. R. Burt, and A. E. Borchart, filed Dec. 6, 1971. Although equivalent foam systems may be used (e.g. other urethane foams), it is preferred to use "ARCOFOAM-1" system having the characteristics indicated in Table VIII below:

TABLE VIII: ARCOFOAM-1

Compression strength (psi) at yield	43-50
Compression at yield	3.5-5.0
Density (pcf)	2.7-2.8
k-Factor, aged (new 0.11-0.13)	0.15 BTU/M/sf°F/in
Closed cells (%)	89.5
Open cells (%)	6.8
Cell Walls (%)	3.7
Curing Time	at least 10-15 min. (here)
Water Vapor Transmission (perms)	3.5

Although other conventional foam spray equipment may be used, a Gusmer pneumatic-mix spray apparatus is preferred here (Gusmer Coating Co., Inc. — Woodbridge, N.J.) having a heater that provides a block temperature of about 140°F. and hose temperature of about 112°-118°F.

This ARCOFOAM 1 system is (as is conventional) developed by mixing and spraying a combination of polymeric isocyanate, (here "ARCOFOAM-ISO-1" is preferred) plus a polyol mixture, (here "ARCOFOAM-OL-1" being preferred) to finally cure on the substrate. ARCOFOAM-OL-1 comprises a mixture of polymeric, polyether polyols containing trichlorofluoromethane catalyst and other additives plus some free isocyanate. ARCOFOAM-ISO-1 is a polymeric isocyanate of heavy viscosity (about 250 centipoise at 65°F). The properties of the resultant rigid foam as applied and polymerized in situ (summarized in Table VIII) may, of course, be substantially met with any other like system.

Where the urethane foam coating may be applied as above for the typical case of simple revegetation (merely the weight of a few inches of back-fill soil being contemplated), a stronger, thicker layer for where any significant weight is to be applied, such as where a foundation for a gravel building pad or road is being formed. In such instances (or where any appre-

ciable moisture is anticipated), it will be preferred to apply the urethane foam in a "multi-laminate" form. For instance, a seven-layer foam about 1.5 inches thick (the specific thickness depending on locale) has been found satisfactory for Prudhoe Bay pond crossings (more below). Here the foam is applied in successive layers (preferred range 4 to 7) each separated by a very high density laminar-skin a few mils thick (formed by sufficient exposure of the upper surface of each layer to air). Of course, moisture should not be present except, perhaps, during the initial application time, the liquid substrate being understood as being solidly frozen thereafter.

PHASE 3 — SEAL

15 The urethane foam layer is then allowed to cure long enough to set up (here about 10 to 15 minutes) and then the protective barrier super-coating, or seal, is applied to protect against degradation of the foam by mechanical and liquid forces. Here, the seal preferably takes the form of ARCO Barrier coat 1000 applied to a continuous uniform thickness of about 15 mils., being applied in the manner of the pre-coat described above and comprising the same material without the polymeric extenders.

20 Now the frozen, insulated sump pond is ready to be covered with soil and reseeded to develop tundra vegetation and thus "restore" the site. It is preferred (though not essential) that this phase of the treatment be performed about "break-up" time (or around May 15 for Prudhoe Bay), since the berm fill will begin to be somewhat thawed and workable about then. This may preferably and conveniently be done simply by rolling-back enough berm material to bring the sump-

25 cavity up to grade since this berm is understood as largely comprised of top-soil (active layer) material intermixed with tundra type organic matter and thus especially well suited for planting. Of course, if necessary, one may haul in gravel, dune sand, etc., to establish the proper reseeding topsoil mix. The fill is preferably piled up slightly above grade so as to accommodate some minor subsidence and water run-off (e.g., from rain and snow melt). Reseeding will be performed in the manner above described except as otherwise noted here.

30 With the sump site now so filled, it is next, according to another feature of novelty, reseeded and fertilized with a prescribed tundra reseeding formulation to induce optimum revegetation and regrowth in the subject locale. Reseeding may be done at any convenient time when the appropriate equipment and personnel can get access to the site, often on the same day the insulation is applied and the sump filled in. The Reseeding Formulation developed for this locale comprises the following generic constituents: a special formulated tundra fertilizer; a localized mixture of cover crop seeds (an annual) which have been germination-induced; and a localized perennial seed mixture, selected for this locale and adapted to induce regrowth that is quick to germinate and grow, is strong, and offers some resistance to winter-kill. This tundra fertilizer is especially formulated to supply the needed nutrients found to be missing in the Prudhoe locale (see soil analysis in Tables II and III, and discussion above). A preferred embodiment is the aforescribed "Tundra Special-70" fertilizer (see Table IV). The preferred embodiment for this "Prudhoe Reseeding Formulation" is "Prudhoe

35

40

45

50

55

60

65

1-C", the constituents and dosages thereof being summarized in Table IX below.

TABLE IX — RESEEDING FORMULA "PRUDHOE 1-C"

ARCO Tundra Special 70 Fertilizer	300 lb./acre
Cover Grass — Annual Rye	50 lb./acre
"Perennials":	
Red Top Grass	8 lb./acre
Creeping Red Fescue Grass	16 lb./acre
Canada Blue Grass	8 lb./acre

The cover crop seed (Rye preferred here) is compatible with the Perennial and is chemically treated before application to accelerate germination as afore-described. The cover crop will act to stabilize the site during initial, delicate regrowth, holding the top-soil and retaining moisture while the perennial seed is taking hold.

The perennial mixture is selected to yield seedlings that are capable of both germinating in the brief Prudhoe summer and offer a high degree of winter survival. The perennial grass seeds (see Table VI also regarding Red Top, Creeping Red Fescue and Canada Blue Grass) are preferably coated with a formulation to accelerate germination rates and increase seedling growth.

While reseeding usually may be performed at any time of the year, some grasses, such as Canada Blue, have been found to suffer inferior germination unless they are exposed to a "freeze cycle," such as when they experience an arctic winter "in the ground" or when they are pre-chilled in cold storage for a time. It is believed that this affects certain enzymes, contributing to good germination. The reseeding formulation may be applied in any known, convenient manner, e.g. being distributed separately and incorporated into the top-soil with a harrow. For small areas like the subject sump, which are also within a few miles of operating base, manual application methods such as broadcasting are feasible. However, for larger areas or those more remote, aerial seeding from helicopter-borne unit will often be advisable, this being followed by ground incorporation, where needed.

For the present embodiment, the Prudhoe 1-C reseeding formulation is preferably applied by manual broadcasting on top-soil of the frozen, filled site without any particular effort at incorporation. This formulation was tailored to the indicated soil analysis and the native tundra vegetation in the Prudhoe Bay locale. It will be understood that for other areas with different vegetative types and/or different soil analysis, appropriate modifications may be made by those skilled in the art. It has been noted that in certain instances some "follow-on care" is also advisable; for instance, where reseeding is followed by an unfavorable growing period (e.g., scanty precipitation, nutrient deficiencies), further fertilization, watering, or even supplemental reseeding, may be called for. In the present embodiment, it will be found that application of this formulation will result in revegetation and restoration of the site, integrating it with the ambient terrestrial environment, providing a solid, stable support under the reseeded soil with the sump liquid being kept frozen and incorporated as (quasi-permafrost — or "icing-in" the sump pool) a part of the adjacent permafrost with no later subsidence, erosion, etc. Of course, this perennial cover vegetation is designed to be superceded eventu-

ally by a "climax cover" of the original native vegetation (re-invasion). Complete tundra regrowth, stability and ecological equilibrium should thus be restored within just a few Arctic seasons.

5 WINTER ROAD RESTORATION

The concepts demonstrated in the foregoing mud sump restoration embodiment may also be applied to other related situations where relatively small, shallow, 10 confined liquid deposits on the frozen plain may be insulation-sealed and rendered into a "quasi permafrost" condition; and then overlain with various construction and/or ground cover materials. One example is restoration of "winter roads" of the type aforedescribed. It 15 will be appreciated that "winter roads" are typically formed simply by scooping up tundra material and top-soil in a strip along the planned road-bed and piling it up to form the roadway (berm). Now, this typically leaves broad ditches paralleling the roadway berm 20 which have been denuded of tundra vegetation. In such instances, and unfortunately, one or two summer seasons will usually develop ground-water pools in the ditches; these will grow with each summer-thaw, inducing run-off and "galloping erosion". It will be apparent 25 that the foregoing system taught for restoration of mud sums may likewise be applied for restoration of such "water ditches." Thus, one may apply the aforementioned insulation system (including a pre-coat and a barrier coat where appropriate) atop the frozen 30 ditch-pools — doing this during the winter freeze and covering the insulation with a suitable soil cover, (e.g., rolling back a part of the winter road berm — now useless and abandoned), and thereafter reseeding and restoring the ground cover with an appropriate restoration 35 system such as that aforedescribed (Table IX etc.).

It will further be apparent to those skilled in the art that such an "icing-in" is applicable not only to "water-ditches" (as with mud sums) but may likewise be applied to other roads (not just "winter roads") or embankments where a "ponded condition" has resulted in depressions along an embankment shoulder or elsewhere; of course adapting the reseeding restoration system in an appropriate manner to suit the given ambient 40 environment.

Moreover, as a further improvement, the foregoing teaching may be adapted for restoring "depressions" on the frozen plain such as the described mud sump, winter road or other rain ditch situations etc., where 45 the depressions are relatively "dry," i.e., they either have no liquid therein or too little to suit (e.g. liquid level below grade). Nonetheless, in such situations where water or other applicable liquid is available for practical use, it will be seen that such a depression may be filled with liquid, then allowed to freeze, then insulated and restored to the surrounding grade and vegetative condition. For instance, during the winter season one may apply liquid in a fine spray to build up quick-frozen layers, creating a "laminar iced-in" system, and 50 so artificially "ice-in" the depression to bring it up close to tundra-grade to be thereafter soil-filled and planted. This ice-in obviously conserves fill material (e.g., gravel which is quite precious in certain areas) 55 quickly and inexpensively. Indeed, such a frozen pond substrate (akin to the sump embodiment) will be recognized by construction engineers as forming a hard, flat, stable, "quasi-permafrost" base which is a fine founda- 60 65

tion for roads, building pads, etc. as long as it is kept frozen. For instance, such an ice footing under a gravel road will provide an especially hard solid, flat stable foundation as long as it is kept frozen. Indeed, in some situations (indicated elsewhere) it may even be desirable to create such a depression, fill it with liquid, freeze it, insulate it and build on this "artificial permafrost" according to the invention.

POND CROSSING

As suggested above, the subject system is applicable for uses beyond simply trapping and stabilizing waste deposits underground (as quasi-permafrost) and will have application as a positive construction technique in certain instances. One of these is the typical "Arctic pond" situation where an Arctic road or embankment is planned across a route intersected by one or more small, shallow depressions, often filled to some extent with liquid and subject to melting. More particularly, and for example, where one is building a gravel road in the Prudhoe Bay locale, he will typically encounter a myriad of such natural ponds creating the well-known "polygon formations" on the North Slope. Such ponds comprise depressions on the order of a few yards in diameter by a few feet deep and these literally dot the Arctic plain! To circumvent all such Arctic ponds in laying out a roadway is usually impossible, and almost never practical — even assuming one is unconcerned over how much time and trouble it takes to snake the road along the ridges between ponds.

Thus, for this "pond crossing" embodiment, it will be understood that a gravel road is contemplated, measuring about 5 feet high by about 15 feet wide (useful width; graded with shoulders extending about 4 feet out on each side — this constituting a gravel berm overall about 23 feet wide). When the typical shallow "polygon pond" is encountered, it may be bracketed (completely covered) by the planned width of this gravel berm. It will be apparent that the aforementioned mud-sump insulation technique, appropriately modified for the given circumstance, may be employed to provide a solid quasi-permafrost base for the road. However, when only part of the pond lies along the path of this berm, it will often be practical to go to special lengths to freeze and insulate (ice-in) the entire pond nonetheless, and cover it with topsoil and revegetation in the pond area not covered by the road-berm — the insulation being accordingly extended across the entire ponded surface to cover (ice-in) those areas not along the path of the intended highway. Ground cover, such as the tundra reseeding system mentioned in the first (pond stabilization) example, may then be superposed.

For such roadway foundations (or related load-bearing sites), it will be preferable to employ about 1.3 inch of the polyurethane mentioned in the first example for better structural support, applying this in a seven-laminate system as described (assuming the Prudhoe Bay locale). However, foam thickness will, of course, depend upon ambient thermal driving conditions and vary with the thermal characteristics and history of the site. For example, at either the Sagwon or the Galbraith locale (in Alaska), the polyurethane insulation thickness will be closer to 2 inches, with the gravel super-cover thickness being determined primarily by structural loading constraints. For heavier loading, and/or in cases where a severe ground moisture condition is con-

templated, greater thicknesses and/or more laminations will be preferred. It should be appreciated by those skilled in the art that, although the aforescribed road construction technique involves the extra expense of insulation (usually relatively minor) and, in certain cases, the expense of revegetation as well (over ponded areas that are wider than the roadway), this will be more than compensated-for by the resultant freedom of design which is achieved and by the associated savings in length-of-road (eliminating winding-about between ponds); as well as savings in bridges or culverts eliminated and by the extra stability supplied by the firm, stable "quasi permafrost" substratum developed.

LEVELING ARCTIC ROADS

The principles of the invention illustrated above may be further applied in the leveling of roadways over tundra, providing an economic and structurally sound means of reducing "cut and fill" problems. Workers in the art know that the North Slope or any such frozen plain typically presents a gently-rolling terrain that undulates up and down (several feet amplitude) regularly, every dozen yards or so in all directions. This undulation creates a "cut and fill" problem for the road engineer, requiring excavation and the need for a great deal of gravel or other fill (note that scraping or related leveling techniques cannot be used since the tundra ground cover must be kept intact). In cases where liquid water is available in the wintertime it will be apparent that, as with the aforescribed "icing-in" of pond crossings (embodiment above), here, the depressions along the roadway may likewise be sprayed with water, frozen-in and insulated to provide an "ice-fill" up to within a few inches of the surrounding grade (being integrated with the subjacent permafrost) being thereafter covered with gravel, etc. It has been found that at least 6 inches of gravel should be applied.

An analogous treatment is advantageous for providing a "quasi-permafrost" footing under an arctic embankment. An example is for constructing a "Building Pad" as follows:

A Pad formulation area 100 × 100 feet is worked out on the Prudhoe Bay tundra in the winter season. Snow is piled up and compacted (sufficient to at least support a man) within this area to a uniform depth of about 3 feet. Liquid water is then sprayed atop this snow pad and allowed to freeze (in layers preferably a few inches thick each) in situ until about two feet of ice is thus built up. Then, generally following the teachings of the prior embodiments (except where specified otherwise), a urethane foam "cap" is laid down atop the ice and down the sides of the "ice-pad" (to the extent it protrudes above-grade), to a thickness of about 1½ inches. A perimeter-form may be employed to contain the ice-fill and give vertical sides where desired. The pad (top and sides) is then covered with a "structural pile" of gravel ("Sagwon" type) about 6–8 inches thick. Next a power house structure is constructed on the gravel pad to house a 30 KW generator complex. This structure will generate heat and must accordingly be thermally-insulated from the so-constructed "quasi-permafrost" foundation. This generator is operated periodically according to need. Using thermo-couple data to monitor temperatures, it will be observed (over at least one or two seasons) that only a slight thawing will occur — this, in the top 2–3 inches of the icepad. Also,

resultant settlement will be found very minor (e.g. about 1-2 inches over two seasons — using normal survey/leveling measurement techniques) with substantially no deterioration of the foam.

The foregoing will be surprising in several respects. It indicates that an "ice-pad" (whether snow-ice as described; simply spray-on ice built up to the desired height, etc.) will provide a very satisfactory base for structures (e.g., embankment base for a drill pad or housing structure). The ease, convenience and time savings (also gravel savings) resulting will especially be appreciated (e.g., ice-in a drill pad during winter; set up operations next summer if desired). Moreover, the efficiency of a urethane foam "cap" (assume foam as previously described) in maintaining the frozen (quasi-permafrost condition of the ice base is demonstrated — even in the face of heat input from a generator structure atop the pad. Of course, a proper "K factor" will be selected. Also, the adequacy of a few inches (6-8 inches described) a gravel top-cover as both a wear surface and "protective mantle" for the foam is shown. Workers in the art will appreciate that such ice-pads can be provided using modified, equivalent expedients. For instance, a berm of snow (or frozen snow) may be provided as a "perimeter barrier" or "form" within which the ice-pad may be built up above grade; whereas, below grade a simple hole will often suffice.

Thus, for greater thermal protection, and as a further feature of novelty, the aforescribed insulation-cap is spray-coated with a "sacrificial layer" of ice (preferably a fraction of one inch) only thick enough to dissipate a prescribed "heat surge" from the structure, yet insufficient to substantially degrade the insulation once-melted; the latent heat of fusion being employed to dissipate calories. A protective hydrophobic coating may also be provided over the insulation and the insulation tilted in one or several directions for quick run-off.

Workers in the art will recognize that the novel features of this disclosure may be applied, alone or together, in other contexts to solve different but related problems and that the implementation suggested in the foregoing embodiments may be modified to achieve the described results. For instance, where roadways were mentioned primarily in the embodiments, it will nonetheless be apparent that the same kind of restoration and construction techniques may be applied for gravel building pads or other embankments on frozen terrain. Similarly, for the insulating material; while urethane foam has been suggested in the embodiments, there will be instances, recognized by those skilled in the art, where other equivalent foams and other insulation can suffice (such as polystyrene foam or even ceramic materials or various natural materials in various forms). In particular, where inexpensive insulation is desired, such coatings as petroleum-extended foams (e.g., extended with "Prudhoe crude") or the like, may be applicable. In certain instances the incorporation of air or other blowing agents will be employed (e.g. conventional air-blowing techniques) so that the active hydrogen content of the material be increased, similar to what is done with asphalt coatings elsewhere. Likewise, although spray-foaming application techniques have been described, workers in the art will in some instances contemplate other application, and/or fabrication, techniques as being satisfactory. Similarly, with

the revegetation techniques, it will be understood that, although those described were apt for the purposes and the locales mentioned, workers in the art will prefer different (though related) seeding and supportive fertilization and germination techniques for substantially different circumstances. For instance, while pre-treating seeds as indicated with gibberellic acid (selectively, however, for each variety) gave rather surprising results (as did pre-treatment with potassium nitrate; in

5 a different way, however), other known germination promoters such as ethylene, Kinetin or Thiourea will occur to workers as somewhat similarly applicable. Such expedients for enhancing germination and growth will be found to be important to a degree much more 10 critical than in other ("non-frigid") environments, for example, the special interaction, on grasses like those mentioned in North Slope regions, of low temperatures (low thaw-index, high freeze-index) with constant high-wind conditions plus harmful insulation (incident radiation on surface-applied, non-incorporated seeds) and rather arid ground conditions are believed to constitute the principal cause of the unusually low germination rates, and/or relatively high residual-germination conditions found to obtain. Also, workers will appreciate 15 the surprisingly advantageous interaction of the described insulation and resotration (e.g., replanting) techniques. For instance, not only does such insulation seal-in a permafrosts substratum and prevent later thaw and erosion from removing (replanted) ground cover, but the regrowth and the insulation supplement one another in certain respects — the vegetation acts as a supplemental thermal shield once established; but, until it is, the insulation accelerates warming of the planted top-soil (adding to the thaw index of the site) and hastens regrowth. In certain instances such a subsurface 20 layer of artificial insulation can also be employed to conserve moisture; for instance, a relatively water-impermeable insulation sheet covered with only a few inches of humus and replanted will obviously enhance 25 insulation for at least a few years in arid regions — e.g., both melting snow cover earlier and conserving more melt run off.

30 In summary, although certain embodiments have been given by way of example and illustration, it will be obvious to those skilled in the art that various modifications of the materials and techniques described may be made without departing from the spirit and scope of the present invention as defined in the appended claims. For example, equivalent elements and steps may be substituted for those described, parts may be reversed 35 and various features used independently of others, all without departing from the spirit of the invention.

40 What is claimed is:

45 1. A method of disposing of a prescribed volume of liquid or semi-liquid waste on the terrain of cold weather regions, this method comprising the steps of:

50 55 60 65 selecting or constructing a prescribed storage cavity in said terrain adapted to receive said volume of waste; filling said cavity with said wastes to a prescribed degree and allowing this deposit to freeze substantially solid at least at the upper level thereof; capping the upper surface of the so-frozen waste deposit with a layer of protective material including a prescribed thickness of artificial thermal insulation, sufficient to keep the deposit frozen and thus forestall melting and subsidence during a pre-

scribed "lifetime" in the subject environment; and covering the so-coated frozen deposit with particulate soil fill to a prescribed level.

2. The method as recited in claim 1 wherein said waste comprises a volume of spent drilling mud and wherein said soil fill has characteristics similar to the native soil.

3. The method as recited in claim 1 wherein said protective layer includes a petroleum base top-seal coating including polymeric materials, this top-seal coating being applied as a weather seal over said insulation.

4. The method as recited in claim 3 wherein said protective layer comprises an initial coating of a crude petroleum product extended with polymeric materials with a few hundredths of an inch thereof being applied to the surface of the frozen deposit; and a one to two inch thickness of a rigid polyurethane foam insulation applied on this initial coating.

5. The method as recited in claim 1 wherein said insulation comprises a rigid polyurethane foam coating applied in several layers and adapted to support a prescribed structural load as well as to resist the intrusion of moisture vapor.

6. The method as recited in claim 1 including the steps of:

providing a perimeter-berm to at least partly define the prescribed cavity; excavating, after freezing of waste deposit held within this perimeter berm, the inner perimeter of the berm to define a ledge extending outward as an annular ring about the top perimeter of the frozen surface and tilted downwardly so as to define the locus of a "brim" annulus of insulation about the insulation cap to be overlaid on the frozen deposit, thereafter so coating the deposit as to define this insulation cap including the outward, downward-extending "brim"; and thereafter applying a particulate soil layer as a protective mantle over the insulation cap and the disposal site.

7. The method of claim 1 wherein said particulate soil fill is treated to enhance early restoration thereon of native ambient ground cover vegetation.

8. The method of claim 1 wherein said particulate soil fill is replanted to induce native revegetation.

9. The method of claim 1 wherein said particulate soil fill is seeded with selected cover-crop seeds.

10. The method of claim 9 wherein said seeds are perennial seeds selected from the group consisting of Red Top, Creeping Red Fescue, Canada Blue and Brome.

11. A method of leveling and stabilizing the surface terrain of areas in the Arctic regions characterized by depressions comprising (a) filling the depressions to a predetermined level with frozen material (b) coating the frozen materials of the filled depression substantially entirely with sufficient artificial insulation material to keep it frozen for a prescribed period of time (c) covering the insulation material with a layer of particulate soil material to bring the level of the filled in depression up to the level of the surrounding terrain and (d) treating said particulate soil material with fertilizer containing those nutrients which are necessary to sustain the growth of desired vegetation and of which said particulate soil is deficient.

12. The method of claim 11 wherein said particulate soil material is seeded with selected cover-crop seeds.

25

13. The method of claim 12 wherein said seeds are perennial seeds selected from the group consisting of Red Top, Creeping Red Fescue, Canada Blue and Brome.

30

14. A method of leveling and stabilizing the surface terrain of areas in the Arctic regions characterized by depressions comprising (a) filling the depressions to a predetermined level with frozen material (b) depositing a layer of polymer-extended petroleum crude material on the frozen material (c) coating the petroleum crude material substantially entirely with sufficient artificial insulation material to keep it frozen for a prescribed period of time and (d) covering the insulation material with a layer of particulate soil material to bring the level of the filled in depression up to the level of the surrounding terrain.
